Primary Examiner — Cynthia M Chin*(74) Attorney, Agent, or Firm* — Panitch Schwarze Belisario & Nadel LLP(57) **CLAIM**

The ornamental design for a wheel cap, as shown and described.

DESCRIPTION

FIG. 1 is a rear perspective view of the wheel cap in accordance with my new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a rear elevational view thereof; and,

FIG. 7 is a front elevational view thereof.

The broken lines in the figures are for illustrative purposes to identify portions of wheel cap that form no part of the claimed design.
